United States Patent Office

Des. 180,968
Patented Sept. 10, 1957

180,968

SNACK TRAY OR THE LIKE

Joseph B. Stier, New York, N. Y.

Application December 10, 1956, Serial No. 44,125

Term of patent 14 years

(Cl. D44—10)

Fig. 1.

Fig. 2.

Fig. 1 is a top perspective view of a snack tray, showing my new design; and

Fig. 2 is an edge view of the same.

I claim:

The ornamental design for a snack tray, as shown.
